22 Claims. (Cl. 255—1.8)

1

This invention relates to a novel method and apparatus for thermally piercing holes in minerals and mineral-like materials.

Holes have been successfully pierced in masses of minerals and mineral-like materials by applying thereto a flame from a blowtorch to separate material from the mass, removing the separated material from the mass to form a hole, and advancing the blowtorch into successive portions of the hole as they are formed to increase its depth. Some rocks, such as quartzite, have been pierced by a spalling process wherein particles of rock are spalled off without fusion and are blown out in an unfused condition. Others, such as iron ore, have been pierced by a process wherein the ore is melted and then either blown out in the melted condition or, preferably, quenched with water in the hole, mechanically disintegrated by the physical impact of rotating teeth, and blown from the hole in a solid condition.

When piercing holes in such materials with a blowtorch it has sometimes been difficult to extend the holes to a great depth, especially when the holes are of large diameter such as seven inches or more. This difficulty has been due in large part to insufficient clearance for passage of the blowtorch when the hole is not concentric with the torch or when projections or cores are left in the hole.

Among the objects of the invention are to provide a novel method and apparatus for piercing in a mass of rock or the like a hole concentric with the blowtorch; and to provide such a method and apparatus for insuring sufficient clearance for the blowtorch even when piercing holes of great diameter, such as greater than seven inches, and great depth, such as 30 feet. Another object is to provide a blowtorch which is so constructed as to supply fluids to the blowtorch nozzle without leakage when the nozzle is rotated relatively to fluid supply conduits. Other objects are to provide a novel construction whereby a piercing blowtorch can be suspended while its nozzle rotates; and whereby the blowtorch nozzle can be rotated while it is advanced downwardly into a hole. Still other objects are to provide a blowtorch having slag disintegrating teeth which are removable and replaceable at will; and to provide such a blowtorch having a plurality of long tubes, and means to compensate for differential thermal expansion of the tubes.

The above and other objects, and the novel features of the invention, will become apparent from the following description, having reference to the accompanying drawings, wherein

2

Fig. 1 is a vertical mid-sectional view of the upper portion of a novel blowtorch in accordance with the invention, down to a transverse break line *a—a*;

5 Fig. 1a is a vertical mid-sectional view of the lower portion of the same blowtorch, extending down from the transverse break line *a—a*;

Figs. 2 and 3 are cross-sectional views taken along the lines 2—2 and 3—3 in Fig. 1;

10 Fig. 4 is a cross-sectional view taken along the line 4—4 in Fig. 1a;

Fig. 5 is an elevational view of the lower end of the blowtorch, partly broken away, as seen from the line 5—5 in Fig. 1a; and

15 Fig. 6 is a longitudinal sectional view of the lower or discharge end of another form of blowtorch embodying the principles of the invention.

In accordance with this invention, there is provided a novel method for thermally piercing a hole of large diameter in a mass of mineral or mineral-like material which method comprises directing flame from a blowtorch against the mass in such a way as to impinge on a continuous area extending from the projected longitudinal axis of the blowtorch radially to a position beyond the extended periphery of the greatest diameter portion of the blowtorch expected to enter the hole. The flame is rotated about the longitudinal axis while advancing the blowtorch into the initially formed circular hole to deepen it, thereby heating and separating material from the mass over the whole of a circular area substantially greater in diameter than the blowtorch. In this way, adequate clearance for the passage of the blowtorch is provided at the sides of the hole, and no cores or projections are left which might stop the advance of the blowtorch.

For performing the method described briefly above, there is provided a novel mineral-piercing blowtorch comprising a body *B* having an inlet for fluid, a fluid conduit or tube *W* journaled at its upper end on the body *B* for rotation relatively thereto, and a nozzle or heating head *N* secured to the lower end of conduit *W* and rotatable therewith. Oxygen and fluid fuel are supplied to nozzle *N* through supply conduits or tubes *O* and *F*, respectively. A plurality of radial teeth *T* are carried on the nozzle *N* for rotation therewith, to break up detritus in a hole being pierced and to ream the sides of the hole. The nozzle *N* has one or more suitable flame ports for directing below the nozzle a heating flame which spreads radially from the center of the hole to a point well beyond the extended periphery of that part of the blowtorch in the hole. As the nozzle

rotates, the flame also rotates about the longitudinal axis of the blowtorch thus sweeping over and uniformly heating the whole of a circular area on the mineral material concentric with the nozzle and of greater diameter than the nozzle with teeth, thus providing a circular hole large enough to accommodate the blowtorch. It is advantageous, especially for holes of large diameter, that at least part of the heating flame be discharged from the nozzle eccentrically, since in this way a larger area is heated than would be possible if only a single flame of the same size were discharged concentrically.

More specifically in accordance with the present invention, the nozzle N comprises an adaptor body 11 over the outside surface of which is threaded a removable and replaceable sleeve 13 carrying several longitudinally extending radial disintegrator teeth T equally spaced about its periphery. A flame tip 15 is threaded into a bore 17 in the bottom of the adaptor body and has a flange 19 which overlies and abuts against the lower end of the adaptor body. The upper end of the adaptor body 11 is threaded over the lower end of the outside conduit W to receive water, which enters a bore 21 and flows through a pair of ducts 23 in the adaptor body 11 to its bottom face. Flame tip 15 has an annular water distributing chamber 25 in the upper surface of the flange 19 which registers with the ducts 23 and conducts water to a plurality of radial water discharge ports 27 which deliver water jets near the lower ends of teeth T for quenching any molten slag and for dampening detritus.

At its upper end the conduit W is secured by bolts 29 to a flange 31 on the lower end of a core 33 which is rotatably mounted in a bore 35 within a barrel 37 constituting the outside portion of the body B. Core 33 is retained within barrel 37 at the top by a nut 39 threaded on the top of the core and resting on an annular bearing plate 41 on the top of the barrel, and at the bottom is retained by the flange 31 which overlies the bottom surface of the barrel.

Water is supplied to the inside of conduit W by a water supply pipe 43 threaded into a radial inlet bore 44 near the lower end of barrel 37. From pipe 43 the water passes to an annular distributing chamber 45 in the internal surface of the barrel, and thence flows through a pair of radial ducts 47 in core 33 to a pair of longitudinal passages 49 which extend downwardly to the lower end of the core and open into the conduit W. Barrel 37 is held against rotation by the supply pipe 43 and as the core 33 rotates within the barrel, ducts 47 remain in register with chamber 45 and water is continually carried to the conduit W and the nozzle N for cooling the blowpipe before it is discharged from ports 27. It is obvious that the distributing chamber 45 could as well be formed in the external surface of core 33, or could be formed half in the core and half in the barrel.

The tip 15 also is provided with a ring of oxygen discharge ducts 51 which are supplied with oxygen by the second conduit or tube O arranged concentrically within conduit W. Conduit O is secured at its lower end, as by brazing, to the adaptor body 11 where it opens into the bore 17, and is secured at its upper end, as by brazing, within a central bore 55 in the core 33. Oxygen is supplied to the conduit O from an oxygen supply pipe 57 threaded into a radial bore 58 near the upper end of barrel 37 and opening into an annular distributing chamber 59 formed in the

internal surface of the barrel. Oxygen passes from the annular chamber 59 into the bore 55 during rotation of the core 33, by way of a radial duct 61, which registers continually with the annular chamber.

When the blowtorch of the invention is positioned within a deep hole, the heat of the flame tends to cause the outside conduit W to expand considerably while the internal conduit O remains relatively cool. Since the inside conduit O is fixed at both ends, it is necessary to compensate for the differences in the thermal expansion and contraction of the two conduits by providing means to permit expansion and contraction of the inside conduit while maintaining tight seals at both of its ends. This is accomplished advantageously by providing an expansible and contractible bellows 63 as an integral part of conduit O at its upper end.

Fuel is supplied to a central discharge passage 65 arranged in tip 15 concentrically with the ring of oxygen discharge ducts 51, by the central supply tube F threaded at its lower end into a bore 68 in the tip and extending upwardly concentrically through the oxygen tube O through the bore 55 in core 33. Tube F projects at its upper end above the top of the core 33 and is coupled by a swing joint 69 of conventional construction to a fuel supply pipe 71 in such a way that while the fuel tube F rotates with the nozzle N, fuel is continually supplied to the upper end of the tube. To prevent leakage of oxygen from the upper end of core 33 past the fuel tube F, packing 73 is held tightly in the space between the fuel tube and the wall of bore 55 by a gland 75 retained by a gland nut 77 which is threaded over the top of the core. Differential expansion of the two conduits W and F is compensated for by lengthwise movement of tube F in the packing 73 and gland 75.

Since the blowtorch described above may be of great length, often being longer than 30 feet, concentricity of the fuel tube F, the oxygen conduit O, and the water conduit W is maintained by suitable spacers. As shown in Fig. 1a, two sets of radial spacers 79 are welded to the central fuel tube F at longitudinally spaced points so that they engage the inside surface of the oxygen conduit O. Similarly, radial spacers 81 are welded to the outside surface of the oxygen conduit O near its upper end and engage the inside surface of the water tube W.

In order to permit core 33 to rotate freely within barrel 37, ball bearings are provided between the core and barrel both above and below each of the supply pipes 43 and 57. For installation and servicing of the bearings the barrel 37 is composed of an upper section 83 and a separate adjoining lower section 85, and each section has sockets at its upper and lower ends to receive the bearings. Likewise, in order to prevent the leakage of fluid through the space between the core 33 and the barrel 37, suitable packings are provided between these members on both sides of the supply pipes 57 and 43.

As shown in Fig. 1, the packing and the bearing below the water inlet pipe 43 are provided by inserting an annular packing disc 87 within the space between the core 33 and the lower barrel section 85 and holding it in place with a bushing 89 threaded into a bore 91. Below bushing 89 a ball bearing 92 is inserted within a counterbore 93 in such a way that the inner race of the bearing fits snugly over core 33 and is rotatable therewith, while the outer race of bearing 92

fits snugly with the wall of the counterbore and is held stationary. A similar construction for the packings and bearings above the water supply pipe 43, and both below and above the oxygen supply pipe 57, is employed.

A blowtorch of the great size and weight required for piercing deep holes in mineral materials, for example, holes 30 feet deep and 9 inches in diameter, cannot be handled manually. Therefore the torch is provided with a non-rotating supporting collar 97 surrounding and engaging the outside conduit W below the barrel 31, and constituting a bearing within which the conduit W rotates during the piercing of a hole. Between collar 97 and conduit W there is a pair of ball bearings 101 and 102 resting on a shoulder 98 and facilitating rotation of the conduit in the collar. Collar 97 is retained in position on the conduit W by a second shoulder formed by a retaining nut 99 threaded over the outside of the conduit and abutting against the top bearing 101. A bail 103 is secured to the collar 97 for suspending the blowtorch from a cable during the piercing of a hole.

The rotating parts of the blowtorch are driven by a driving mechanism such as a motor-driven gear 104 rotating a horizontal table 105 having a hexagonal hole 106 receiving a hexagonal drive bushing 107. Drive bushing 107 is secured to the outside conduit W of the blowtorch by a plurality of cylindrical keys 109 which fit within longitudinal grooves or keyways 111 in the external surface of the outside conduit W and within corresponding grooves 113 in the inside surface of the drive bushing. With this construction the drive bushing 107 and keys 109 are freely movable lengthwise of the blowtorch but cannot rotate on the outside conduit W. Therefore, as the depth of a hole being pierced increases, the blowtorch can be lowered through the drive bushing 107 while the latter continues to transmit motion from table 105 to the blowtorch.

In the operation of the blowtorch described in detail hereinabove, deep holes are pierced vertically downward in a body of mineral material, such as iron ore, by discharging oxygen and a combustible fluid such as kerosene from the tip 15 to mix together below the tip and form upon combustion a flame of the diffusion type which melts the mineral material and forms a fluid slag. The hot gases of combustion force the fluid slag out of the melting zone and upwardly to a position such that water jets from the ducts 27 strike the slag, quench it, and at least partially solidify it. The quenched and solidified slag is then mechanically disintegrated by the rotating teeth T, and the disintegrated slag particles are blown upwardly in a solid condition around the blowtorch to the top of the hole, by the gaseous products of combustion and the steam formed by evaporation of water in the hole. As the hole becomes deeper, the blowtorch is lowered to maintain a substantially constant spacing of the nozzle N from the bottom of the hole. This can be accomplished in any suitable way, as by lengthening the cable which is secured to the bail 103.

When a hole of relatively large diameter such as seven inches or greater is to be pierced, the oxygen and fuel are discharged from the nozzle in such a way as to produce an eccentrically located flame which sweeps over a large circular area during rotation of the nozzle. Even when a substantially axially directed flame is used, as

for piercing holes of smaller diameter such as about three inches, any inaccuracy which might cause eccentric discharge of the flame from the tip is compensated for by rotation of the nozzle during the piercing of a hole.

When the mineral mass being pierced is of a type which is wholly or partially heat-spallable, the spalled off particles in the unfused condition are merely damped by the water from ports 27 and then blown from the hole.

When teeth A are worn or when a different type of teeth is wanted for any operation, sleeve 13 can be removed from adaptor body 11 and replaced by another sleeve having the proper teeth. Also when flame tip 15 is damaged, or when a different type of flame is desired, it can be threaded out of bore 17 and replaced by a suitable new tip.

Fig. 6 shows another type of blowtorch nozzle 20 N' that can be used in place of the nozzle N shown in Figs. 1 and 1a. Nozzle N' is designed with an internal combustion chamber 113 into which fluid fuel and combustion-supporting gas are injected from passages 115 and 117, respectively.

Upon combustion of the fuel in chamber 113 an axial flame is discharged from the nozzle through an axial passage 119; and a second flame is discharged eccentrically from the nozzle through a second passage 121 that makes an angle of about 25 degrees with the longitudinal nozzle axis. With this flame pattern, a continuous area of rock is heated extending radially from the center of a hole, marked by the extended longitudinal axis of the blowpipe, to a position well beyond the periphery of the disintegrator teeth 123. Water for cooling and for quenching slag is supplied through an outside conduit 125 and is discharged from nozzle N' through a plurality of circumferentially arranged ports (not shown).

Using a nozzle N' of the type shown in Fig. 6, having a diameter of six inches, a hole 30 feet deep and between eight and nine inches in diameter was successfully pierced at a rate of 27.5 feet per hour in the stratified taconite ore of the upper cherty division of the Biwabick iron ore formation of the Mesabi Range by melting, quenching, and mechanically disintegrating the ore. Kerosene was used as the fuel and oxygen as the combustion-supporting gas.

In contrast, when an attempt was made under the same conditions, but with a nozzle discharging only an axial flame, no progress could be made. Also under the same conditions, but using a nozzle discharging a single flame at an angle of 20 degrees to the longitudinal axis, a hole three feet deep and seven inches in diameter was pierced at a rate of only nine inches per minute, and the hole could not be extended deeper than three feet because a crown of ore formed in its center and impeded the blowtorch.

Specific embodiments of our novel blowtorch have been described hereinabove by way of illustration only. It is to be understood that changes in the construction and arrangement of parts, and in the method of operation, can be effected by persons skilled in the art.

We claim:

1. In a blowtorch, a body having an inlet for fluid; a fluid conduit journalled at one end on said body for rotation relatively thereto; said body having passage means so constructed and arranged as to maintain communication between said inlet and said conduit during rotation of said conduit; and a heating flame head secured to the opposite end of said conduit and rotatable there-

with said flame head having port means in an external surface thereof for discharging such fluid therefrom.

2. In a blowtorch, a body having an inlet for fluid; a fluid conduit journalled at one end on said body for rotation relatively thereto; said body having passage means so constructed and arranged as to maintain communication between said inlet and said conduit during rotation of said conduit; and a heating nozzle secured to the opposite end of said conduit and rotatable therewith, said nozzle having a flame port so constructed and arranged as to project flame eccentrically therefrom.

3. In a blowtorch in accordance with claim 1, a supporting collar on said conduit separate from said body and head, said collar constituting a bearing within which said conduit rotates.

4. In a blowtorch, a barrel member having an internal peripheral surface; a core member rotatably mounted in said barrel member and having an external peripheral surface adjoining said internal surface; a heating flame nozzle spaced from said core member and having port means in an external surface thereof for discharging fluid therefrom; a conduit secured to both said core member and said nozzle whereby said core member, conduit, and nozzle are rotatable together as a unit; said barrel member having a first inlet for fluid; said core member having a first duct extending to the inside of said conduit for supplying fluid to said conduit; and one of said members having a first annular chamber in one of said adjoining surfaces communicating with both said first inlet and said first duct during rotation of said core in said barrel.

5. In a blowtorch in accordance with claim 4, packing between said external peripheral surface of said core and said internal peripheral surface of said barrel on both sides of said annular chamber preventing fluid leakage during rotation of said core.

6. In a blowtorch in accordance with claim 5, bearings between said core and said barrel facilitating rotation of said core.

7. In a blowtorch in accordance with claim 8, said barrel member comprising separate adjoining upper and lower sections; said blowtorch comprising bearings and packings between said core and said barrel in each of said sections on both sides of each of said annular chambers.

8. In a blowtorch in accordance with claim 4, a tube within said conduit connected to both said core member and said nozzle and rotatable therewith; said barrel member having a second inlet for fluid spaced from said first inlet; said core member having a second duct extending to the inside of said tube; and one of said members having a second annular chamber in one of said adjoining surfaces communicating with both said second inlet and said second duct during rotation of said core member.

9. In a blowtorch in accordance with claim 8, means permitting expansion and contraction of said tube while maintaining tight seals between said tube and said core member and nozzle.

10. In a blowtorch in accordance with claim 8, a second conduit within said first-named conduit connected at one end to said nozzle and rotatable therewith, said second conduit extending through said core member; a fluid supply conduit; and a coupling between said fluid supply conduit and the top of said second conduit so constructed and arranged as to permit said second conduit to

rotate with respect to said fluid supply conduit while fluid is supplied thereto.

11. In a blowtorch, a nozzle adapted to project flame therefrom; a rotatable conduit engaging said nozzle at one end thereof; a shoulder on said conduit and a supporting collar on said conduit between said nozzle and said shoulder, said collar abutting against said shoulder and constituting a bearing within which said conduit rotates.

12. In a blowtorch in accordance with claim 11, a bail carried by said collar for suspending said blowtorch in vertical position while said conduit rotates with respect to said collar and said bail.

13. In a blowtorch, a body having an inlet for fluid; a fluid conduit journalled at one end on said body for rotation relatively thereto; said body having passage means so constructed and arranged as to maintain communication between said inlet and said conduit during rotation of said conduit; a nozzle secured to the opposite end of said conduit and rotatable therewith, said nozzle having a flame port for projecting flame therefrom; and at least one keyway on the outside of said conduit extending approximately the full length thereof.

14. In a blowtorch, a body having an inlet for fluid; a fluid conduit journalled at one end on said body for rotation relatively thereto; said body having passage means so constructed and arranged as to maintain communication between said inlet and said conduit during rotation of said conduit; a nozzle secured to the opposite end of said conduit and rotatable therewith, said nozzle having a flame port for projecting flame therefrom; and a drive bushing gripping said conduit, the construction and arrangement being such that said drive bushing and conduit rotate together while said drive bushing is free to move on said conduit lengthwise thereof.

15. In a blowtorch in accordance with claim 14, driving mechanism engaging said drive bushing for rotating said bushing and conduit.

16. In a blowtorch, an adaptor body; a first tube and two other tubes within said first tube, all terminating at their front ends at said adaptor body and projecting rearwardly therefrom; a supply conduit for water connected to said first tube; a supply conduit for fuel connected to one of the inside tubes; a supply conduit for combustion-supporting gas connected to the other of the inside tubes; said supply conduits and said tubes being so constructed and arranged that said tubes are rotatable with respect to said supply conduits; a nozzle tip secured to said adaptor body in communication with said tubes, said tip being removable and replaceable at will; and teeth projecting from said blowtorch near the front end thereof.

17. In a blowtorch in accordance with claim 16, said teeth being mounted on a sleeve, said sleeve being removable and replaceable at will on said blowtorch.

18. In a method of thermally piercing a hole in a mass of rock by applying thereto flame from a heating device, separating material from said mass by said flame, removing the separated material from said mass to form a hole, and advancing said flame into successive portions of said hole as formed to increase the depth thereof, the improvement comprising forming and directing the flame from the end of the heating device at least in part eccentrically of the longitudinal axis of the heating device; and continuously rotating said flame about the longitudinal axis of

said heating device during its advance to assure formation of a hole concentric with said heating device.

19. In a method of thermally piercing a hole in a mass of rock by applying thereto flame from a heating device, separating material from said mass by said flame, removing the separated material from said mass to form a hole, and advancing said heating device into successive portions of said hole as formed to increase the depth thereof, the improvement comprising directing said flame from said heating device as an axial flame jet and a second flame jet at an angle to said axial flame jet in such a way as to impinge on a continuous area of said mass extending from the center of said hole radially to a position beyond the extended periphery of the greatest diameter portion of said blowtorch expected to enter said hole, and rotating said flame about the longitudinal axis of said blowtorch while advancing said blowtorch, thereby heating and separating material from said mass over a circular area concentric with and of greater diameter than said blowtorch.

20. In a method of thermally piercing a hole in a mass of rock by applying thereto flame from a heating device, separating material from said mass by said flame, removing the separated material from said mass to form a hole, and advancing said flame into successive portions of said hole as formed to increase the depth thereof, the improvement comprising projecting said flame eccentrically from said heating device and rotating said flame about the longitudinal axis of said heating device during its advance to assure formation of a hole of larger diameter than, and concentric with, said heating device.

21. In a method of thermally piercing a hole

in a mass of rock by applying thereto flame from a heating device, separating material from said mass by said flame, removing the separated material from said mass to form a hole, and advancing said heating device into successive portions of said hole as formed to increase the depth thereof, the improvement comprising: directing said flame from said heating device as a plurality of flame jets, at least one of said flame jets being directed eccentrically with respect to the longitudinal axis of said heating device, and rotating said flame jets about the longitudinal axis of said heating device while advancing said heating device, said flame jets being so directed from said heating device as to impinge on and sweep over a continuous circular area of said mass in front of, and of greater diameter than, said heating device to heat and separate material from said mass over said circular area.

15 22. In a method in accordance with claim 21, said eccentrically directed flame jet diverging at an angle from the longitudinal axis of said heating device.
